(57) **CLAIM**

The ornamental design for a sensing faucet for integration of soap supply with water exit, as shown and described.

DESCRIPTION

FIG. 1 is a perspective view of a sensing faucet for integration of soap supply with water exit showing our new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; and, FIG. 7 is a bottom plan view thereof.
The portions shown in broken lines form no part of the claimed design.
